UNITED STATES PATENT OFFICE.

JOHN RUFUS BLOCKER, OF AUSTIN, TEXAS.

FIRING MECHANISM FOR GUNS.

No. 895,947.

Specification of Letters Patent. Patented Aug. 11, 1908.

Application filed July 16, 1907. Serial No. 383,992.

To all whom it may concern:

Be it known that I, JOHN RUFUS BLOCKER, a citizen of the United States, and a resident of Austin, in the county of Travis and State of Texas, have invented a new and Improved Firing Mechanism for Guns, of which the following is a full, clear, and exact description.

My invention relates to fire arms and especially to double-barrel shotguns, my more particular object being to employ a single trigger and parts associated therewith, so arranged that the operator may have complete control over the order in which the barrels are successively discharged and in which any predetermined order may be changed at will without the necessity for opening or "breaking" the gun.

By use of my invention as applied to a double-barrel shotgun a sportsman may, by predetermined arrangement of the parts, fire first the right barrel and next the left barrel by simply pulling the trigger twice in succession, and by another predetermined arrangement of the parts, made at will and almost instantly, he can fire first the left barrel and then the right barrel by merely pulling the trigger twice in succession.

In order to make clear the structure and operation of the parts, it may be well to bear in mind that a double-barrel shotgun may be relative to its loading in any one of several different conditions. For instance, both barrels may be loaded, the right barrel may be discharged leaving the left barrel only as loaded, the left barrel alone may be discharged leaving the right barrel only as loaded, or both barrels may be discharged. Again a sportsman handling the gun may desire to fire the barrels in succession, first the right and then the left, or first the left and then the right, or he may desire to fire either the right or the left barrel alone, the other barrel having already been fired, or having both barrels loaded he may desire to fire one barrel only.

Reference is to be had to the accompanying drawings forming a part of this specification, in which similar characters of reference indicate corresponding parts in all the figures.

Figure 1 is a fragmentary side elevation, partly in section, showing a double-barrel shotgun as viewed from the left-hand side of the gun, a portion of the handle of the gun being broken away, this view showing the parts as arranged when the gun is ready to be

fired, so that if the trigger be pulled twice in succession, the right barrel will first be fired and this will be followed by the discharge of the left barrel; Fig. 2 is a view from the opposite or right side of the gun, the parts remaining in the position just mentioned; Fig. 3 is a fragmentary view showing the gun as partly broken away, the principal parts constituting the firing mechanism being viewed from the left of the gun and in such position that pulling the trigger will discharge the left barrel, the right barrel having already been fired; Fig. 4 is a view somewhat similar to Fig. 1, but showing the hand-controlled switch as moved backwardly, so that pulling the trigger twice in succession will fire the barrels successively in the order left, right, this view further showing the safety catch as moved backward so as to prevent the trigger from being pulled and consequently to temporarily prevent the gun from being discharged; Fig. 5 is a fragmentary view showing the parts as viewed from the right side of the gun and arranged to fire the barrels in the order left, right, the left barrel, however, having already been discharged so that a single pull of the trigger must discharge the right barrel; Fig. 6 is a fragmentary section upon the line 6—6 of Fig. 1, looking in the direction of the arrow and showing the relative arrangement of the sears, sear levers and parts immediately associated therewith; Fig. 7 is an enlarged perspective of the cam used for holding the manually operated switch in either of its two positions; and Fig. 8 is an enlarged fragmentary side elevation showing the rear portion of the manually-operated switch as held in one of its positions by aid of the cam.

A portion of the left barrel is shown at 9 and a portion of the right barrel at 10, a casing at 11 and recoil lugs integral with this casing at 12. A handle is shown fragmentarily at 13 and at its top and bottom are frame ribs 14, 15. A trigger guard is shown at 16. Hammers 17 are concealed within the casing, the gun in this instance being of the so-called "hammerless" type. Sears are shown at 18, 19. The hammers and sears are in this instance shown as they appear in the ordinary Remington double-barrel shotgun and need no detail description. Suffice it to say that the right-hand sear 19 and the left-hand sear 18 control the release of the respective hammers associated with the barrels.

with these sears, thereby causing the discharge of the respective right and left barrels.

My invention therefore begins with the rearmost ends of the sears, my purpose, 5 incidental to the control by the operator over the discharging of the barrels, being incidentally to enable him to raise the sears 18, 19 in any order he chooses.

A break lever 20 is provided with a bearing 21 (see Figs. 5, 6) whereby it is journaled in position upon the casing 11, this break lever and parts controllable by it being each of the usual pattern, found, for instance, upon the well-known Remington gun, and 15 the lever 20 is normally held in a central position by a leaf spring 22 also of well-known construction.

A safety slide 23 is milled upon its upper surface and is provided with depending lugs 20 24, 26, the lug 24 having a stop pin 25 projecting laterally from it. Both of these lugs project downwardly through a slot 27. A leaf spring 28, secured against the under side of the frame rib 14, engages the stop pin 25 25 and not only holds the safety slide 23 in either of its two extreme positions, but also presses this slide firmly downward and holds it steadily in position.

A fork 29 is secured rigidly upon the frame 30 rib 15. Pivoted within this fork by means of a pin 30, and free to rock, is a safety lever 31. A safety dolly 32, having substantially the form of a flat bar, is connected by a pivot pin 33 with the safety lever 31. This safety 35 dolly is pushed backward, as in hammerless guns heretofore used by the ordinary thrust rod (not shown) housed within the casing 11 and operated by opening and closing the gun. This rearward movement of the dolly, incidental to opening the gun (for instance in 40 loading), causes the lower end or toe of the lever 31 to project forward over the trigger so that the latter can not be pulled backward so as to fire the gun. The upper end of the 45 safety lever 31 is provided with a head 34 which projects intermediate of the lugs 24, 26. When the safety slide 23 is moved backward, as in Fig. 4, the lower end of the safety lever 31 is forced forward, and vice versa, 50 when the slide 23 is moved forward the lower end of the safety lever 31 is moved rearwardly.

A brace bolt 35 and a lug 36 connect together the upper frame rib 14 and the lower 55 frame rib 15. A plate 37, slightly curved, is provided with a milled head 38 whereby it may be moved forward or backward a slight distance. For this purpose the plate 37 is provided with a slot 39 and through this slot 60 a screw 40 extends into the frame rib 15. The operator, by placing his thumb upon the head 38 may move the plate 37 either forward or backward. This plate and parts carried by it I designate as a manually- 65 operated switch.

A trigger is shown at 41 and is mounted integrally upon a trigger plate 42, the latter being pivoted upon a pin 43 and free to rock when the trigger is pulled. Lugs 43^a support the pivot pin 43 and thus serve as a mounting for one end of the trigger plate. 73

Mounted centrally upon the plate 37 and integral therewith is a plate 44 provided with a vertical slot 45 and further provided with another slot 46 the latter terminating at its top in an angle 47. A leaf spring 48 is connected by a pivot 49 with an eccentric 51, the latter having lugs 50 integral therewith and disposed upon its opposite sides (see Figs. 7 and 8). As the spring 48 presses upward, 53 the eccentric 51 tends to hold the plate 44, and consequently the plate 37, in their extreme forward or backward positions, as the case may be, so that when the plate 37 is moved either forward or backward, it remains firmly in position until the operator 35 purposely moves the head 38.

Sear levers are shown at 52, 53 and are used for lifting the respective sears 18, 19. The sear lever 52 is provided with two hooks 54, 55 integral therewith and extending upwardly therefrom. Similarly the sear lever 53 is provided with hooks 56, 57, extending upwardly from it and integral with it. The trigger lever 42 is provided with a plate 58 95 integral therewith and extending upwardly from the rear thereof. This plate 58 extends through the dolly 32, the latter being slotted for the purpose, and moves upwardly a slight distance whenever the trigger 41 is pulled, 100 provided, of course, that the safety slide 23 is in its forward position, as indicated in Fig. 5.

Moving the safety slide 23 to its rearmost position (see Fig. 4) causes the lower end of the safety lever 31 to advance and project 105 over the portion of the trigger lever. This prevents the trigger from being pulled. The plate 58 carries four hooks 59, 60, 61, 62 (see Figs. 4 and 5), these hooks being pivoted upon it. The hooks 59, 62 are integral with 110 each other and have substantially the form of an inverted U. Similarly the hooks 60, 61 are integral with each other and have the form of an inverted U. The hooks 59, 60, 61, 62 are respectively disposed adjacent to 115 the hooks 54, 55, 56, 57 carried by the sear levers.

A leaf spring 63 is secured to the plate 58 and presses the hooks 60, 61 toward the rear. A wire spring 64 is connected with the lug 36 120 and presses downwardly against the trigger plate so as to hold the latter, and consequently the trigger, in their respective normal positions.

A latch 65 is pivotally mounted upon the 125 lug 36 and is pressed upwardly by a leaf spring 66. This latch extends rearwardly from the lug 36 and is provided with a shoulder 67 which is adapted to lodge against a stop pin 68 mounted upon the fork 29. A 130

pin 69 (see Fig. 5) mounted upon the hook 61 and extending laterally therefrom, projects over a portion of the latch 65. The purpose of the latch 65 is to engage the pin 69 and thus 5 at times to prevent the hook 61 from moving into engagement with the hook 56. The hook 59 (see Fig. 4) is provided with a pin 70 which projects laterally through the slot 45 in the plate 44 and thus enables the hook 49 10 to be rocked whenever the plate 37 is moved by aid of the head 38.

The operation of my device is as follows: I will assume that both barrels of the gun are loaded, and that the safety slide 23 is in its 15 forward position or "shooting" position, and that the operator desires to discharge them in the order right, left. He moves the head 38 forward, as indicated in Figs. 1 and 3. Now, having all of the parts in their respective positions, as indicated in Figs. 1 and 3, he pulls the trigger. Nothing occurs to raise the sear lever 52 and consequently the left barrel of the gun can not be fired at this time. This is because the hooks 59, 60 (see Fig. 1) 20 are out of engagement with the hooks 54, 55. The pin 70 extending through the slot 45 and the manually-operated switch (controllable by the head 38) being forward, the hook 59 can not possibly touch the hook 54. Neither 25 can the hook 60 engage the hook 55 for the reason that the pin 69 is restrained by the latch 65 (see Fig. 2). In this connection it should be remembered that the hooks 60, 61 are integral and consequently whatever will 30 restrain the hook 61 must necessarily prevent engagement of the hook 60 with its mating hook 55. Upon the right side of the gun, however, the situation is different. Here, it is true, the hook 61 can not engage its mating 35 hook 56 but it is also true that the hook 62 is in engagement with its mating hook 57. Consequently, when the pull of the trigger causes the trigger lever and the plate 58 to rise, the hook 62 in carrying up its mating 40 hook 57 raises the sear lever 53 and trips the sear 45 lever 19, causing the right-hand barrel 10 to be discharged. The movement of the trigger necessary to accomplish this result in raising the plate 58 causes the latch 65 to release the 50 pin 69 for the reason that the shoulder 67 of the latch 65 is unable to follow and lodges against the stop pin 68, and the latch is unable to rise higher, so that the pin 69 now clears the latch and moves to a point a little 55 higher than the highest portion of the same. When, however, the pressure of the finger upon the trigger is relaxed, the spring 64 moves the trigger lever back into its normal position and the two hooks 60, 61, being 60 pressed rearwardly by the leaf spring 63, now engage the two hooks 55, 56. The latch 65 is unable to prevent this movement of the hooks just mentioned, for the reason that the 65 pin 69 in descending now lodges upon a lug 65^a and consequently can not assume the po-

sition, relatively to the latch 65, that it has in Fig. 2. The pin 69 thus carries the latch 65 downwardly. The right barrel having been discharged as above described, the operator now pulls the trigger again. The 70 hooks 60, 61 being now in engagement with the hooks 55, 56, both sear levers 52, 53 are raised, and, consequently, both sears 18, 19, are tripped. Since, however, the right barrel is already empty, the left barrel only is 75 fired. Such being the case, it follows that with the parts arranged as indicated in Figs. 1 and 2, two successive pulls of the trigger result in discharging first the right barrel and then the left barrel. Suppose, now, that 80 both barrels are loaded and that the operator wishes to put the gun in such condition that by pulling the trigger twice in succession, first the left barrel and next the right barrel will be fired. The operator places his 85 thumb upon the head 38 and forces it toward the rear of the gun. In doing this the plate 44 (see Fig. 8) turns the cam 51 slightly in a clockwise direction, according to this figure, the lugs 50 being thrown to the right. The 90 pin 70 being encompassed within the slot 45 is also, by this movement, moved toward the rear of the gun. Hence, the hook 59 carrying the pin 70 is moved toward the rear of the gun, and as the hook 59 is integral with the 95 hook 62 the hook 59 is brought into engagement with the hook 54, while at the same instant the hook 62 is moved out of engagement with its mating hook 57. The trigger is now pulled. The right sear 19 can not be 100 raised for the reason that the hooks 61, 62 are out of engagement with the hooks 56, 57, yet the hook 59 is in engagement with the hook 54 (see Fig. 4). Hence, the pulling of the trigger causes the hook 59 to lift the hook 105 54, raise the sear lever 52 and trip the sear 18, thus discharging the left barrel. The upward movement of the pin 69 causes it to rise above the latch 65, and this allows the hooks 60, 61 to swing back into engagement 110 with the hooks 55, 56. Another pull of the trigger causes the two hooks last mentioned to be raised, thus raising both sear levers and tripping both sears, the right barrel only being the one now fired, owing to the fact 115 that the left barrel is empty. It can never happen that both barrels will be fired at the same time, for the reason that when both barrels are loaded and the safety slide is in position for shooting, it is impossible to raise both sear levers at the same instant. In firing, the two sear levers are pulled, first one alone, and then both together. After the last barrel is fired it is 120 true that the hooks 60, 61 are both left in engagement with the mating hooks controlling the sear levers, but this fact does not enable both sear levers to be raised at once. The act of opening the gun for the purpose of re-loading must necessarily take place before 125 130

the gun can be fired again, and this act of opening the gun causes the safety dolly 32 to be pushed to the rear as in other double guns of the hammerless type, and this movement 5 of the dolly causes the lower end of the safety lever 31 to press forward and to disengage both of the hooks 60, 62. This movement of the safety lever shifts the safety slide 23 to the rear and disengages the hooks 60, 61 10 from these mating hooks. Now, when the safety slide is next moved by hand toward the front for the purpose of placing the gun in condition to fire, the immediate reengagement of the hooks 60, 62 with their mating 15 hooks is prevented by the action of the latch 65^a and pin 69 as above described. The trigger being now pulled, neither of the hooks 60 or 62 can have any effect upon either of the sear levers, and the result is that when the 20 trigger is pulled, the gun is fired independently of the action of the hooks 60 and 62 so that the simultaneous discharge of both barrels, due to any disturbing action at this juncture, by the hooks 60 or 62, is effectively 25 prevented.

Having thus described my invention, I claim as new and desire to secure by Letters Patent:

1. In a fire arm, the combination of a plurality of barrels, a single trigger, a plate movable by said trigger, a pair of hooks connected rigidly together and pivotally mounted upon said plate, a second pair of hooks connected rigidly together and pivotally mounted upon said plate, said second pair of hooks being movable independently of said first-mentioned pair of hooks, a plurality of sears, a sear lever for each sear, said sear lever being provided with two hooks adapted to be

engaged respectively by one hook of each 40 pair, and means controllable by the operator for bringing one hook of each pair successively into engagement with its corresponding hook upon said sear lever so as to pull the said sear levers in a predetermined order. 45

2. The combination of a pair of sear levers, each provided with two hooks, a trigger provided with a portion disposed intermediate said sear levers, hooks arranged in pairs and pivotally mounted upon said portion of said 50 trigger, the hooks of each pair being rigid in relation to each other, and means controllable by the operator for moving said hooks mounted upon said portion of said trigger in a predetermined order of succession for the 55 purpose of enabling said trigger to actuate said sear levers in a predetermined order.

3. In a fire arm, the combination of a trigger provided with an extending portion, hooks pivotally mounted upon said extending portion, a sear lever provided with hooks to be engaged by said last-mentioned hooks, a slidable member for changing the relative position of one of said hooks mounted upon said portion of said trigger, said slidable 65 member being provided with an opening, a cam having a portion disposed within said opening, and a spring connected with said cam for holding said slide temporarily in a predetermined position. 70

In testimony whereof I have signed my name to this specification in the presence of two subscribing witnesses.

JOHN RUFUS BLOCKER.
